Specification of Letters Patent.

Patented Sept. 2, 1913.

Application filed April 26, 1912. Serial No. 693,886.

To all whom it may concern:

Be it known that we, GEORGE A. DOBYNE and STEPHEN A. DOBYNE, citizens of the United States, and residing at St. Louis, in the State of Missouri, have invented certain new and useful Improvements in Shoe-Nails, of which the following is a specification.

This invention relates to nails, and more particularly to shoe nails.

10 In the manufacture of shoes, more particularly in the operation of attaching soles of McKay shoes, the fastening means are passed through the outsole, tapsole, upper and insole. The attaching seam must lie 15 as close to the outsole as possible in order to make a tight seam, and in order to present a neat appearance. Where the seam is a metallic seam, *i. e.*, formed by a row of metallic fasteners or nails, the clenched points 20 of the nails will lie on the insole close to the inside surface of the upper. Now it is necessary that the clenched points extend along the seam in order to produce a flexible and neat shoe. It is therefore necessary to 25 accurately control the clench of the nail so as to produce this result. The clenching anvil used with shoe machines is of that type having a clenching surface in the form of a segment 30 of a sphere. Such a spherical clenching anvil is necessary in order that the shoe supporting horn may be rotated as the shoe 35 is being nailed. Such an anvil will not however by itself accurately control the direction of the clench, but the point of the nail is liable to turn sidewise to a more or less extent, and may pass through the upper and thus ruin the shoe.

The objects of this invention therefore are to produce a nail which is so constructed that 40 it will itself control the direction of the clench, whereby it is insured that the nail will be clenched in a predetermined direction.

Further objects will appear from the detailed description taken in connection with the accompanying drawing in which:

Figures 1 and 2 are views of the nail, Fig. 2 being an enlarged detail of the point formed on the nail, and Fig. 3 is a section 50 through the sole of a McKay shoe attached by means of the nail forming the subject matter of this invention.

Referring to the accompanying drawing, the nail as shown comprises a shank 10 having a laterally extending head beveling to

the shank as shown at 12. The shank tapers slightly to its point 13 and this point is slightly turned or deflected in the direction of its head. This bend is formed as fully described in our application Serial No. 724,680, 60 filed October 8, 1912. In the operation of forming the nail as described in said application the point is comparatively blunt and the bend given this point is so abrupt that one edge of the point is deflected laterally to form in effect the extreme point of the nail as shown at 14.

The horn used with shoe machines is provided with a clenching anvil having a clenching surface in the form of a segment 70 of a sphere. If the nail formed as described above is driven through leather and the point thereof strikes an anvil, this turned point will clench in the direction given to it by the turn. Such a clenched point is shown 75 at 15 Fig. 3, which shows the nail driven through the layers of leather in a McKay shoe. The turn given the point 13 must be short and sharp. This turn must be sufficient to cause the direction of clench to be 80 predetermined and to cause the point to clench in the direction given it by this preliminary turn, but must not be sufficient to cause the nail to turn or curl while passing through the material. The turn must be 85 such that the actual clenching is done by the anvil, and the nail must not turn or curl while passing through the material. In other words the direction and the amount of the turn on the point of the nail must be 90 sufficient to cause it to be clenched in a predetermined direction, but not greater. The turn need only be slight, and by keeping the turn slight, sharp and short, the desired results are obtained. The nail when formed 95 in the nail making machine is made by cutting pieces out of one edge of a strip or ribbon. In view of the fact that one edge of the nail will therefore be uncut and rolled and the other side cut, the cut side will be 100 the weaker, and the nail will bend toward the cut side. This will to some extent promote the clenching of the nail point in the direction of the laterally extending head.

It is obvious that various changes may be 105 made in the details of the nail, within the scope of the claims, without departing from the spirit of this invention, and it is therefore to be understood that this invention is not to be limited to the specific details shown 110

and described except as required by the claims.

Having thus described the invention what is claimed is:

5. 1. A shoe-nail having its point deflected an amount sufficient to predetermine the direction of its clench by an anvil but not sufficient to cause the point to turn while passing through the material.
10. 2. A shoe-nail having a laterally extending head, and having its point deflected laterally in the direction of the head an amount sufficient to predetermine the direction of its clench by an anvil but not sufficient to cause the point to turn while passing through the material.
15. 3. A shoe-nail having one of its edges cut

and having its point deflected laterally toward the cut edge an amount sufficient to predetermine the direction of its clench by an anvil but not sufficient to cause the point to turn while passing through the material.

4. A shoe nail having a comparatively blunt point deflected laterally an amount sufficient to predetermine the direction of its clench by an anvil.

In testimony whereof we affix our signatures in presence of two witnesses.

GEORGE A. DOBYNE.
STEPHEN A. DOBYNE.
